Filed June 16, 1967, Ser. No. 7,491

Term of patent 14 years

(Cl. D37—3)

FIG. 1 is a top plan view of a rotary brush ring embodying my new design.

FIG. 2 is a side elevational view thereof.

FIG. 3 is a vertical sectional view taken in the plane indicated by line III—III of FIG. 1.

FIG. 4 is a vertical sectional view taken in the plane indicated by line IV—IV of FIG. 1.

FIG. 5 is a bottom plan view thereof.

The broken lines shown on the drawing are for illustrative purposes only.

It is to be understood that the perforations shown partially applied to the bottom of the ring in FIG. 5 covers the entire area encompassed thereby.

We claim:

The ornamental design for a rotary brush ring, as shown and described.
